UNITED STATES PATENT OFFICE.

ALFRED JAMES DOHERTY, JR., OF MACKINAC ISLAND, MICHIGAN.

ADJUSTABLE CASTER.

1,185,886.

Specification of Letters Patent.

Patented June 6, 1916.

Application filed April 10, 1916. Serial No. 90,149.

To all whom it may concern:

Be it known that I, ALFRED J. DOHERTY, Jr., a citizen of the United States of America, residing at Mackinac Island, in the county of Mackinac and State of Michigan, have invented new and useful Improvements in Adjustable Casters, of which the following is a specification.

The present invention relates to improvements in adjustable casters, and is designed particularly for use in connection with certain pieces of furniture.

The primary object of the invention is the provision of adjustable means for use in connection with furniture such as phonograph cabinets, desks, tables, etc., by which the piece of furniture may be adjusted to level position, and particularly in the case of phonograph cabinets, the cabinet may be adjusted so that when the motor is wound, the cabinet remains stable or rigid.

In utilizing my invention, the piece of furniture is equipped with the adjustable casters by applying them to each of the supporting legs or pedestal of the furniture, and inasmuch as each caster is adjustable independently of the others, it will readily be seen that the piece of furniture may be positioned to rest upon a floor, and be adjusted to the irregularities in the flooring, so that the article will stand without shaking or vibrating.

The invention consists in certain novel combinations and arrangements of parts for attaching the caster to the leg of the piece of furniture as will be hereinafter more fully described and claimed.

In the accompanying drawings I have illustrated one complete example of the physical embodiment of my invention constructed according to the best mode I have so far devised for the practical application of the principles of my invention.

Figure 1 is a side elevation of a caster constructed according to my invention and shown as applied to the lower end of a leg of a piece of furniture. Fig. 2 is a view seen from the right in Fig. 1, showing parts of the invention in section, and also the leg. Fig. 3 is a top plan view of the adjustable caster. Fig. 4 is a side elevation of the socket member detached. Fig. 5 is a side elevation of the adjusting screw member, detached.

In the preferred embodiment of my invention, I have illustrated the roller 1 and

its bracket 2 as of usual construction, and the stem 3 has a rivet head 3^a in the bracket 2, while its upper end 3^b may be riveted or headed as illustrated to hold the stem in the hollow screw sleeve 4. This sleeve with its external threads and hollow bore, is formed with a hollow cap 5 which is circular in cross section and knurled on its exterior so that it may be grasped by the fingers and thumb to be turned. The usual antifriction rollers 6 and supporting members 7 and 8 are inclosed within the hollow cap 5, and supported on the stem 3, and the antifriction rollers or disks 6 revolve it around in a circle on the upper edge of the bracket 2 as usual. These parts are all loose with relation to each other, so that the threaded sleeve 4, the two members 7 and 8, and the stem 3 are all supported on the bracket head 2, but they are all free to revolve with relation to the bracket with the stem as a center, and the stem itself is loose in the bracket and threaded sleeve 4.

The portion of the adjustable caster which is fixed to the piece of furniture, comprises a barrel or socket 9, which is internally screw threaded, and provided with an enlarged head 10, which is preferably of frusto conical form to give a finished appearance to the lower end of the leg of the piece of furniture to which it is attached. This head is provided with a series of upwardly projecting prongs 12 which may be driven into the material of the leg 13, and the leg itself is bored out to form a socket to receive the barrel 9. By means of the prongs 12, the barrel 9 is securely fixed to the lower end of the leg 13, and then the threaded sleeve 4 is entered and screwed into the barrel 9. Thus, in order to adjust a desk on an irregular floor, if the roller 1 does not touch the floor, the threaded sleeve 4 may be screwed out of the barrel 9 until the roller 1 is brought down in contact with the floor. In this manner, if a table with four legs has three legs resting on the floor, and the other leg due to an irregularity in the floor is not touching the floor, the adjustable caster may be manipulated so that the fourth leg will perform its proper functions in supporting the table, and when thus supported at its four points, the table remains rigid and stable.

This device is particularly applicable for use in connection with cabinets for sound reproducing machines or other instruments

of precision where it is necessary that the body to be supported shall be steady and stable and insured against tilting or shaking.

5 What I claim is:

The combination with a furniture leg having a socket of a barrel provided with internal threads, and means for fastening the barrel to said leg, a roller and its sup-

porting bracket, a rotatable sleeve having 10 exterior threads engaging the interior threads of the barrel, a stem securing the bracket and sleeve together, a hollow cap on the sleeve, and antifriction bearings between said cap and the bracket.

15

In testimony whereof I affix my signature.

ALFRED JAMES DOHERTY, JR.
